UNITED STATES PATENT OFFICE.

ROBERT M. ROBINSON, OF LOUISVILLE, KENTUCKY, ASSIGNOR TO CHEATHAM ELECTRIC SWITCHING DEVICE CO., INCORPORATED, OF LOUISVILLE, KENTUCKY, A CORPORATION OF KENTUCKY.

GROUND BOX.

Original application filed December 22, 1923, Serial No. 682,235. Divided and this application filed June 8, 1925. Serial No. 35,766.

An object of my invention is to provide a ground box with a toggle joint of a novel kind in connection with switches for street railways and the like. Heretofore a toggle 5 has been employed which is spring pressed so as to keep a switch point rail at one limit or the other of its movement and prevent its stopping at dead center. A toggle embodying my invention is articulated so as to give 10 an additional movement to the member which is directly driven by the compression spring so as to allow a stronger spring action to be obtained than is normally the case with the attendant greater security.

15 A further object of my invention is to provide means for a quick replacement of the bearing and fulcrum means of the lever when wear develops. This and other objects are accomplished by my invention, one embodiment of which is hereinafter more particularly set forth.

For a more particular description of my invention, reference is to be had to the accompanying drawings, forming a part hereof, 25 in which

Figure 1 is a plan view of a ground box embodying my invention.

Figure 2 is an enlarged plan view of the fulcrum and journal shown in Figure 1.

30 Throughout the various views of the drawings, similar reference characters designate similar parts.

The switch throwing lever 6 has a downwardly extending fulcrum 7 which is suitably journaled against a base block 8 which is preferably integral with the casing 2 and this block 8 is slotted to receive a bolt 9 that holds a journal jaw 10 which has its other end resting against a projection 11 which 35 runs parallel to the part 8, but slightly separated therefrom, as shown in Figure 1. This jaw 10 can be adjusted by a nut on the bolt 9 so as to bear against a large bushing 7a in which the fulcrum 7 may move freely. The 40 jaw 10 can be firmly clamped against this bushing by means of bolt 9 and at the same time bushing may be easily renewed by loosening the nut at the back of bolt 9 swinging jaw 10 away from bushing and lifting bushing 45 out.

While I am aware that other means have been made for the quick replacement of the bushing of a ground box lever, they have been found to be wanting in respect to per-

manency i. e. under the very severe pounding by the force exerted by the plunger and the resistance offered by the switch point, the bolt and clamp means become loosened. In my device where a superior leverage is effected by reason of holding jaw 10 at its 55 extreme ends, the entire device remains fixed until removed for replacement of the bushing. Attention is called to the fact that by my arrangement the maximum amount of clamping force for the space available is procured. It is even greatly superior to using bolts at 60 each end of jaw 10 for securing it to part 8. Please note the fulcrum point of 10 as being at the most remote point against an 65 absolutely solid member 11 which is cast integrally with the ground part and part 8. A further point of superiority in my device resides in the fact that even though two bolts were used, it would necessarily place the second one in close proximity to the adjacent 70 wall of the ground part thereby not giving sufficient room for an ordinary wrench to operate a standard nut of the bolt to the desired tightness. Still another point of superiority 75 is procured through the relative less expense of my device over additional and unnecessary parts which would have been used by the application of obvious means.

While I have shown and described one embodiment of my invention, it is obvious 80 that it is not restricted thereto, but that it is broad enough to cover all structures that come within the scope of the annexed claims.

Having thus described my invention, what 85 I claim is:

1. In a switch throw mechanism comprising a lever connected to the switch and fulcrumed in a bushing carried by an integral ground box constructed with a grooved block 90 and a lug projecting from one wall of the ground box, a grooved jaw with one end abutting said lug and the other end formed for the reception of a bolt, a bushing interposed in the grooves of said jaw and said block 95 between the ends of said jaw and a bolt so located and disposed as to clamp the bushing 100 between the jaw and the block.

2. In a switch throw mechanism comprising a lever connected to the switch and fulcrumed in a bushing carried by an integral ground box constructed with a grooved block 105 and a lug projecting from one wall of the

ground box, with the adjacent bottom area closed, a grooved jaw with one end abutting said lug and the other end formed for the reception of a bolt, a bushing interposed in 5 the grooves of said jaw and said block between the ends of said jaw and a bolt so located and disposed as to clamp the bush-

ing between the jaw and the block, said bushing being so disposed as to have its lower end closed by said adjacent bottom area.

10

In testimony whereof, I have hereunto set my hand this 10th day of April, 1925.

ROBERT M. ROBINSON.
